UNITED STATES PATENT OFFICE

2,187,474

APPARATUS FOR HAIR WAVING

Ralph M. Keele, San Francisco, Calif., assignor,
by direct and mesne assignments, to Keelmo
Co., San Francisco, Calif., a corporation of
California

Application May 16, 1936, Serial No. 80,129
Renewed June 13, 1938

9 Claims. (Cl. 132—36)

This invention relates to apparatus for so-called "permanent" waving hair on the human head, and particularly pertains to that type of such apparatus for practicing what is known as the Croquignole method of "permanent" waving. In this method of waving hair, the hair is treated with a softening solution and is then divided into flat strands and a protector pad and clamp is applied to the base of each strand closely adjacent to the scalp to protect the scalp and to hold the strand for further treatment. Each strand of hair is then wound flatwise from its free end to the clamp on a curler spindle which is then usually connected with the clamp and turned to place the hair under tension. The wound strand together with moisture is then enclosed in what is usually termed a heater, and heat is applied to a degree sufficient to vaporize the moisture and cause it to penetrate the wound strand and effect the wave.

The process of waving hair and apparatus for practicing it just described is the most commonly employed and has a number of shortcomings. These shortcomings are principally due to the provision of the pads and clamps which, due to their length and thickness, obviously prevents the wave from being spaced a uniform short distance from the scalp. Further, the application of such pads and clamps consumes considerable time of the operator's time, and the weight thereof on the head adds to the discomfort of the waving operations.

It is the principal object of my present invention to provide an improved and highly efficient apparatus for use in practicing the Croquignole method of "permanent" waving, which apparatus effects a superior form of wave and overcomes the shortcomings of the apparatus heretofore employed, in that it simplifies the operations required to effect a wave so as to minimize the time required to wave a head of hair, permits the application of a greater number of curlers to be applied to a head of hair than can be applied by use of prior methods and apparatus so that a wave may be produced which will be uniformly spaced and comparatively close to the scalp, and which apparatus reduces the weight applied to the head so as to reduce the discomfort of the waving operations.

One form which the invention may assume is exemplified in the following description and illustrated by way of example in the accompanying drawing, in which:

Fig. 1 is a perspective view of a heater unit embodying the preferred form of my invention.

Fig. 2 is a perspective view of the casing portion of the heater unit.

Fig. 3 is an enlarged transverse sectional view through the heater unit taken on line III—III of Fig. 4.

Fig. 4 is an enlarged central longitudinal section through the heater unit taken on line IV—IV of Fig. 3.

Referring more particularly to the accompanying drawing, 10 indicates a heater unit forming the major part of the apparatus constituting the subject matter of my invention. This heater unit includes a hollow casing 11, most clearly illustrated in Figs. 2 and 3, which is substantially rectangular in outline with a thickness somewhat less than its width. The marginal side edges of this casing 11 are semi-cylindrical and the curvature of both the exterior and interior of such edges is carried out as illustrated to give the effect of two hollow cylinders arranged with their axes parallel and with their adjacent side walls intersecting along a line which is at a distance from the centers of said cylinders which is just slightly less than half the diameter of the cylinders. Thus, the interior of said casing forms a substantially cylindrical and elongated charging chamber 12 and a substantially cylindrical and elongated curling chamber 14, which chambers are arranged side by side in parallelism and in direct communication with each other through the elongated narrowed opening 15 between them.

The end walls 16 of the casing are substantially flat although they mold into the marginal edges at one side of the casing as indicated. The end walls and the side walls of the casing 11 are integrally formed of resilient vulcanized rubber. Each of the end walls is formed with a circular opening 17, which openings are in axial alignment and disposed concentric with relation to the curling chamber 14. Between these openings and the adjacent marginal edges of the casing, the end walls are centrally divided as at 18 and said adjacent marginal edge is correspondingly centrally and longitudinally divided so that the portions of the casing at opposite sides of the division constitutes two complementary clamping lips 18a and 18b, which may be separated in a direction at right angles to the axis of the curler chamber so that the casing may be fitted over a curler spindle as will be hereinafter described.

The casing 11 of the heater unit is enclosed in a heater unit frame 19 which comprises two complementary rigid jaw sections 20, which are spaced apart to receive the casing 11 therebetween. These jaws are preferably formed of pressed sheet

metal or molded Bakelite, or a like substance having sufficient strength and rigidity, and are of a formation that they snugly nest over the sides of the casing as illustrated. At the side of the casing 11 opposite the clamping lips thereof, the jaw sections 20 of the frame are each formed with a projecting grip member 21, which are located substantially midway between the opposite ends of the jaw sections. Substantially at the junction between the grip members 21 and the jaw sections 20, the latter are formed with inturned complementary hinge lugs 22 which are hinged together to articulately connect the jaws so that the latter may be relatively moved.

15 The side edges of the jaws opposite the hinge connection therebetween are curved inwardly and are detachably united with the clamping lips 18a and 18b of the casing 11. From the drawing it will be noticed that at the edges of these clamping 20 lips they are longitudinally grooved to receive the inturned edges of the jaw sections 20, and complementary connecting means are formed on these inturned edges and in the grooves to form a detachable connection between the lips and jaw sections. This connection is such that when the 25 jaw sections are relatively moved, the clamping lips of the casing will be moved in unison therewith. Consequently, by moving the two grip members 21 toward each other, the clamping lips 30 of the casing will be spread apart sufficiently to enable the casing to be positioned over a curler.

Spring means 23 is provided between the grip members 21 which normally tends to maintain the clamping lips of the casing in clamping relation through the medium, of course, of the rigid 35 jaw sections 20.

At the outer side of each jaw section 20 I provide a spacer clamp member 24 formed of sheet material of suitable qualities, which spacer 40 clamp members lie closely adjacent to the outer surfaces of the jaws 20 and which extend outwardly a spaced distance from the inturned edges of the jaw members 20. At this point the spacer clamp members are inturned to provide clamping edges 25 which are arranged parallel to and 45 at a spaced distance outwardly from the clamping lips of the casing 11. It will be noticed that the clamping edges 25 of the spacer clamp members are provided with detachable rubber covers as illustrated.

50 The spacer clamp members are slightly resilient so that the clamping lips 18a and 18b of the casing 11 and the spacer clamping edges 25 will both tightly grip a strand of hair regardless of whether 55 the thickness of the strand of hair is greater at the point where it is gripped by the spacer clamp than at the point where it is gripped by the clamping lips of the casing 11.

For use in connection with this heater unit 60 I provide a curler spindle 26 most clearly illustrated in Fig. 4. This curler spindle has a curling surface which is a hyperboloid of revolution with its larger diameter at its ends. At each extremity the curler spindle 26 is formed with an enlarged 65 circular head 27, between which heads and the curling surface the spindle is formed with bearing pins 28 which are reduced in diameter relative to the end of the adjacent curling surface. The diameter of these bearing pins 28 is just slightly 70 greater than the circular openings 17 formed in the end walls of the casing, so that when the casing 11 is arranged over the curler, the edges of the circular openings 17 will register with the bearing pins 28 and yieldably grip them so as to maintain the curler concentrically within the 75

curling chamber and prevent the curler from rotating. It should be stated that this yieldable gripping action between the edges of the openings 17 and the bearing pins 28 enables the curler to be turned by manually gripping one end thereon to take up any slack in the hair after the curler has been positioned and gripped within the casing 11.

Pivoted at one end to the curling surface of the spindle 26 is a clamping tongue 29 arranged 10 to lie closely adjacent to the curling surface of the curler spindle to enable the end of a strand of hair to be clamped to the spindle at the beginning of the winding operation.

I contemplate using heat generated electrically 15 or by chemical reaction within the heating unit to effect the permanency of the wave, both methods being commonly used at the present time in this art. In utilizing heat generated electrically, the curler spindle 26 is formed interiorly with 20 an electrical heating element, which element is fitted with two contact tongues 30 projecting from one end thereof as illustrated for detachable connection with a socket connected by a conductor cord to a source of electrical supply. 25

When it is intended to use heat generated by chemical reaction, I employ apparatus such as described and claimed in a companion application entitled "Method and apparatus for hair waving," filed May 16, 1936, bearing Ser. No. 30 80,128.

When I generate heat within the casing 11 electrically, an absorbent cartridge 32 is dipped in the same solution that the hair is treated with and placed in the heating chamber of the casing 11. The heat generated in the casing, due to the electrical heating element in the curler, vaporizes the solution, creating the hot vapors essential to give permanency to the wave. The absorbent cartridge may be of any suitable absorbent material.

In operation of my apparatus, it is constructed substantially as illustrated and described. The hair is treated with the proper solution, the strength of which determines the tightness of 45 the wave. The hair is then divided into strands and each strand is wound on a curler 26 from its outer end to the scalp. A heating unit is then applied over the curler with the circular openings 17 receiving the bearing pins 28 and securing the 50 curler with the hair wound thereon concentrically within the curling chamber of the casing 11. In the event that electrically generated heat is to be utilized, a cartridge soaked in the same solution that the hair was treated with would 55 first be inserted into the heating chamber of the casing.

It is obvious that as soon as the heating unit is applied to the curler that the strand will be tightly clamped just beneath the curler by the 60 clamping lips of the casing 11 urged toward each other by the spring-pressed jaws comprising the frame of the unit. Likewise, the spacer clamping edges 25 will tightly grip the strand closely adjacent to the scalp, maintaining a spacing between the scalp and the clamping lips of the casing. This provides a double seal to prevent any escaping hot vapors from contacting the scalp.

It is obvious that due to the provision of these 70 clamping devices formed as an integral part of the heater unit, that the operations of previously applying protector clamps and pads has been eliminated, thus effecting a considerable saving of the operator's time. Likewise, by eliminating 75

the use of protector clamps and pads, the strands of hair are not bunched at the scalp so that the wave will be spaced a uniformly close distance to the scalp, thus giving a more natural appearance and effect.

It should also be pointed out that my heating unit with its clamping mediums will be considerably lighter in weight than the combined weights of prior heaters, clamps and protector pads, consequently lessening the discomfiture of the "permanent" waving operations.

After the heating unit has been applied to the curler as previously described, the curler may be slightly turned by manually gripping one of the heads thereon to take up any slack on the hair wound thereon. The yielding gripping action between the edges of the openings 17 and the bearing pins 28 on the curlers will maintain the curler in a set position.

In the event that the heat within the casing is to be generated electrically, the curler is connected with a source of electricity as previously described and maintained for a sufficient period of time to give permanency to the curl. The supply of fluid within the casing 11, which is greater than now utilized, maintains an even steaming temperature and results in a superior wave.

After the hair has been properly steamed, to remove the heating unit it is only necessary to grip the grip members and spread the jaw members of the frame and remove the unit from the curler. The curler is then unwound and detached from the hair and the wave is ready for setting.

Here also an operation is saved in that the operator need not remove any clamps or protectors from the head, consequently expediting the entire operation of giving a "permanent" wave to a head of hair.

From the foregoing it is obvious that I have provided an improved and highly efficient apparatus for use in practicing the Croquignole method of "permanent" waving, by which apparatus I am enabled to produce a superior form of wave. Likewise, it is apparent that my improved apparatus overcomes the shortcomings of prior apparatus heretofore employed in that it reduces and simplifies the operations required to effect such a wave and therefore minimizes the time required to wave a head of hair.

Further, I desire to point out that by the use of my apparatus, a greater number of curlers may be applied to a given head of hair than could be applied by use of prior methods and apparatus so that the wave which I produce will be closely and uniformly spaced from the scalp.

Further, by use of my apparatus the weight on the head is less than the weight applied by prior methods, and consequently minimizes the discomfort of the "permanent" waving operations.

While I have shown the preferred form of my apparatus, it is to be understood that various changes may be made in its construction by those skilled in the art without departing from the spirit of the invention, as defined in the appended claims.

Having thus described my invention, what I claim and desire to secure by Letters Patent is:

1. A heater unit for hair waving apparatus comprising a hollow casing, the interior thereof forming a curling chamber in which a curler may be disposed, said casing being divided longitudinally of said curling chamber to form opposed clamping lips at one side of said chamber, a pair of opposed clamping members arranged parallel to and in alignment with said lips and spaced a

distance outwardly therefrom, and a frame operatively associated with said clamping lips and with the said clamping members to manipulate the same in unison.

2. A hair waving apparatus comprising a heater unit including a hollow casing, the interior of which forms a charging chamber and a curling chamber lying side by side in parallelism and in direct communication, said casing being divided longitudinally of the curling chamber to form a pair of opposed clamping lips at one side of said chamber which may be spread apart to open the curling chamber for the insertion of a curler spindle, said casing being formed of resilient material, a pair of articulately connected rigid jaw members embracing said casing and connected thereto at said lips and normally urging said lips toward each other, a pair of spacer clamp members carried by said jaws and having clamping edges disposed parallel to and in alignment with said clamping lips, said clamping edges disposed at a spaced distance from said clamping lips, said spacer clamp members being yielding in the direction in which the clamping lips move relative to each other.

3. A heater unit for hair waving apparatus comprising a hollow casing formed of flexible material, the interior thereof forming an elongated curling chamber in which a curler spindle may be disposed, said casing being divided longitudinally of said curling chamber to form opposed clamping lips at one side of said chamber, a pair of opposed clamping members arranged parallel to and in alignment with said lips and spaced a distance outwardly therefrom, and a pair of articulately connected jaws operatively associated with said clamping lips and with the said clamping members to manipulate the same in unison.

4. A hair waving apparatus comprising a heater unit including a hollow casing, the interior thereof forming an elongated curling chamber, said casing having aligned openings at opposite ends of said chamber and substantially coaxially thereof, a curler spindle having ends adapted to be yieldably gripped in said openings whereby it will be supported substantially coaxially within said chamber, said casing being divided longitudinally of said curling chamber and centrally of said openings and forming a pair of opposed clamping lips, a pair of opposed clamping members arranged in alignment and in parallelism to said lips at a spaced distance therefrom, and an operative connection between said lips and said members whereby they will operate in unison.

5. A hair waving apparatus comprising a heater unit including a hollow casing formed of vulcanized rubber, the interior of which forms an elongated curling chamber, said casing having aligned openings at opposite ends of said chamber and substantially coaxially thereof, a curler spindle having ends adapted to be received in said openings whereby it will be supported substantially coaxially within said chamber, said casing being divided longitudinally of the curling chamber and substantially centrally of the openings at one side thereof to form a pair of opposed clamping lips, a frame embracing said casing and including a pair of rigid side sections articulately connected, said side sections being connected with said casing at said clamping lips, springs means associated with said side sections constantly tending to urge said clamping lips toward each other, and spacer clamp members carried by said side sections, said members being

yielding in the direction in which said sections are relatively movable.

6. A hair waving apparatus comprising a heater unit including a hollow casing, the interior of which forms a charging chamber and a curling chamber lying side by side in parallelism and in direct communication, said casing being divided longitudinally of the curling chamber to form a pair of opposed clamping lips at one side of said chamber which may be spread apart to open the curling chamber for the insertion of a curler spindle, a pair of articulately connected rigid members connected with said casing and connected thereto at said lips and normally urging said lips toward each other, a pair of spacer clamp members carried by said rigid members and having clamping edges disposed parallel to and in alignment with said clamping lips, said clamping edges disposed at a spaced distance from said clamping lips, means for charging said charging chamber with moisture, and means for generating heat within said casing.

7. A hair waving apparatus comprising a heater unit including a hollow casing, the interior of which forms a charging chamber and a curling chamber lying side by side in parallelism and in direct communication, said casing being divided longitudinally of the curling chamber to form a pair of opposed clamping lips at one side of said chamber which may be spread apart to open the curling chamber for the insertion of a curler spindle, said casing being formed of resilient material, a pair of articulately connected rigid jaw members embracing said casing and connected thereto at said lips and normally urging said lips toward each other, a pair of spacer clamp members carried by said jaws and having clamping edges disposed parallel to and in alignment with said clamping lips, said clamping edges disposed at a spaced distance from said clamping lips, said spacer clamp members being yielding in the direction in which the clamping lips move relative to each other, a moisture charging cartridge removably fitting said charging chamber, and means for generating heat within the interior of said casing.

8. A hair waving apparatus comprising a heater unit including a hollow casing, the interior of which forms a heating chamber and a curling chamber lying side by side in parallelism and in direct communication, said casing being divided longitudinally of the curling chamber to form a pair of opposed clamping lips at one side of said chamber which may be spread apart to open the curling chamber for the insertion of a curler spindle, a pair of articulately connected rigid members connected with said casing and connected thereto at said lips and normally urging said lips toward each other, a pair of spacer clamp members carried by said rigid members and having clamping edges disposed parallel to and in alignment with said clamping lips, said clamping edges disposed at a spaced distance from said clamping lips, and an exothermic heating element insertable into said heating chamber.

9. A hair waving apparatus comprising a heater unit including a hollow casing, the interior of which forms a longitudinally disposed heating chamber and a longitudinally disposed curling chamber lying side by side in parallelism and in direct communication, said casing being divided longitudinally of the curling chamber at the side thereof opposite the heating chamber to form a pair of opposed clamping lips which may be spread apart to open the curling chamber for the insertion of a curler spindle, said casing being formed of resilient material, a pair of articulately connected rigid jaw members embracing said casing and connected thereto at said lips and normally urging said lips toward each other, a pair of spacer clamp members carried by said jaws and having clamping edges disposed parallel to and in alignment with said clamping lips, said clamping edges disposed at a spaced distance from said clamping lips, said spacer clamp members being yielding in the direction in which the clamping lips move relative to each other, and an exothermic heating element removably fitting said heating chamber.

RALPH M. KEELE. 45
